CLAIM

The ornamental design for an antenna housing, as shown and described.

DESCRIPTION

FIG. 1 is a first perspective view of an antenna housing, according to our new design;

FIG. 2 is a second perspective view thereof;

FIG. 3 is a third perspective view thereof;

FIG. 4 is a front elevation view thereof;

FIG. 5 is a left side elevation view thereof;

FIG. 6 is a top plan view thereof;

FIG. 7 is a bottom plan view thereof;

FIG. 8 is a right side elevation view thereof; and,

FIG. 9 is a rear elevation view thereof.

The broken lines show unclaimed environmental structure and form no part of the claimed design.
